UNITED STATES PATENT OFFICE.

HERBERT B. NICHOLS, OF METHUEN, MASSACHUSETTS, ASSIGNOR OF ONE-HALF TO
HENRY C. DOUGHTY, OF EAST PEPPERELL, MASSACHUSETTS.

ADJUSTABLE SINGLE-PEDESTAL FURNITURE.

1,242,024.

Specification of Letters Patent.

Patented Oct. 2, 1917.

Application filed September 20, 1916. Serial No. 121,273.

To all whom it may concern:

Be it known that I, HERBERT B. NICHOLS, a citizen of the United States, residing at Methuen, in the county of Essex and State 5 of Massachusetts, have invented new and useful Improvements in Adjustable Single-Pedestal Furniture, of which the following is a specification.

This invention relates to improvements in 10 adjustable single pedestal furniture, such for instance as school desks and chairs and typewriter tables and chairs, and of that class in which a desk, table, or the like and a seat or chair are both supported by and 15 vertically adjustable on a single pedestal, the object of the invention being to effect the improvements in the construction of the pedestal and of the desk and seat adjusting means.

20 The invention consists in the features of construction, combination, and arrangement of devices, hereinafter fully described and claimed:

In the accompanying drawings:—

25 Figure 1 is a side elevation of an adjustable school desk, school seat, and single pedestal support therefor, constructed and arranged in accordance with my invention.

Fig. 2 is a detail plan of the desk bracket.

30 Fig. 3 is a vertical sectional view of the standard and the desk and chair brackets and their securing dogs on a larger scale and on the plane indicated by the line 3—3 of Fig. 2.

35 Fig. 4 is a detail sectional view on the planes indicated by the line 4—4 of Fig. 3.

Fig. 5 is a detail perspective view of one of the dogs.

Fig. 6 is a detail plan of the seat bracket.

40 The pedestal 1 is in accordance with my invention provided in opposite sides with vertical slots 2 and with a vertical series of ratchet teeth 3 in the said slots, the points of the ratchet teeth being spaced from the 45 periphery of the pedestal.

A pair of brackets 4, 5, are carried by and vertically adjustable on the pedestal, the said brackets projecting in opposite directions from the pedestal and the bracket 50 4 being here shown as supporting a school desk 6, the bracket 5 being shown as supporting a school seat 7 which has a back 8. Various articles of furniture may be supported by the brackets in accordance with 55 my invention and within the scope of the

appended claims. The said brackets may also be of any suitable construction; the bracket 4 is shown as provided with oppositely curved arms 9 and the bracket 5 is shown as comprising a single arm 10 having 60 lateral extensions 11 at opposite sides. The said brackets are provided with suitable screw holes to enable the articles of furniture to be securely fastened thereon.

Each bracket has a hub portion 12, provided with a vertical central opening, through which the pedestal extends, and each bracket is vertically adjustable on the pedestal so that the seat and desk or other articles of furniture carried on the brackets 65 may be adjusted vertically as may be desired and thus adapted for the convenience and use of persons of various heights. In opposite sides of each bracket hub are vertical inwardly opening slots 13, each of said 70 slots having a widened upper portion 14. Said slots are coincident with the slots 2 of the pedestal. In each slot 13 is a dog 75 15 which is pivotally mounted as at 16 and which comprises a lower arm 17 adapted to enter one of the slots 2 and engage the ratchet teeth 3. Each dog also has a widened upper arm 18 arranged for movement in the broadened upper portion of the slot and also arranged at a suitable angle 80 19 with respect to the lower arm 17. Each upper arm has an outwardly extending button 19 which is normally arranged in an opening 20 to the bracket hub and which 85 communicates with the widened upper portion 14 of the slot. The dogs have their lower ends 17 normally held in engaged position with reference to the ratchet teeth by means of springs 21. The arms 17 of the dogs are of the same width as the slots 2 90 of the pedestal and the narrowed lower portions of the bracket slots so that said dogs when engaged coact with the slots 2 to prevent turning movement of the brackets on the pedestal.

When it is desired to move either of the brackets upwardly, the dogs permit such movement and coact with the ratchet teeth to support the bracket in such adjusted position. If it be desired to lower either of the 105 brackets, this may be done by first depressing the buttons 19 of the dogs of such bracket, thus causing the upper arms of the dogs to bear against the periphery of the pedestal and the lower arms of the dogs to 110

move outwardly against the tension of the springs 21 and thus disengage the pedestal teeth. The bracket hubs are here shown as also provided with clamping screws 22 for engagement with the pedestal and to assist in securing the brackets and the articles of furniture carried thereby in the desired vertical adjustments.

While I have herein described a preferred embodiment of my invention I would have it understood that changes may be made in the form, proportion and construction of the several parts within the scope of the appended claims.

Having described the invention, what is claimed is:

1. In a device of the class described, a pedestal having a slot and teeth in the bottom of said slot in combination with a bracket adjustable on the pedestal and having an opening through which the pedestal extends, said bracket also having a slot provided with a portion coextensive in width with and also coincident with the pedestal slot, and also having a broadened portion, and a dog pivotally mounted in the slot of the bracket and having a relatively narrow portion in the narrow portion of said bracket slot and to enter the pedestal slot and engage a tooth, the dog being further

provided with a broadened portion arranged in the broadened portion of the bracket slot and adapted to bear against the pedestal, when the dog is turned to disengaged position.

2. In a device of the class described, a pedestal having a slot and teeth in the bottom of said slot in combination with a bracket adjustable on the pedestal and having an opening through which the pedestal extends, said bracket also having a slot provided with a portion coextensive in width with and also coincident with the pedestal slot, and also having a broadened portion, and a dog pivotally mounted in the slot of the bracket and having a relatively narrow portion in the narrow portion of said bracket slot and to enter the pedestal slot and engage a tooth, the dog being further provided with a broadened portion arranged in the broadened portion of the bracket slot and adapted to bear against the pedestal, when the dog is turned to disengaged position, said broadened portion of the dog also having a press button on its outer side and said bracket having an opening to clear said press button.

In testimony whereof I affix my signature.

HERBERT B. NICHOLS.
